BUOYANT BATHING IMPLEMENT

Emma C. Hegewaldt, Cleveland, Ohio

Application July 18, 1932, Serial No. 623,221

1 Claim. (Cl. 9—11)

This invention relates in general to buoyant water amusement devices and more particularly to a buoyant boat-like bathing implement. The general object of the invention is to provide a 5 buoyant bathing implement adapted to securely support and float a person partly emerged in water. Another object of the invention is the provision of a buoyant bathing implement of the kind referred to having an open bottom and supporting means arranged beyond the lower edge of the implement to insure a structure with a low center of gravity for eliminating danger of capsizing, when a person is seated in said device upon said supporting means thereof. Still another object 10 of the invention is the provision of a buoyant bathing implement of the kind referred to with an air inflated rubber tube to increase the buoyancy of the implement, and means to insure proper attachment of the rubber tube to said implement while protecting the intake valve of said tube against accidental operation.

With these and other objects in view the invention consists in certain novel and useful features of construction and combination of parts all as 15 hereinafter more fully described and more concisely pointed out in the appended claim. In order that the invention may more fully be understood reference is to be had to the accompanying drawing, in which:—

30 Figure 1 is a plan view of the buoyant boat-like bathing implement according to the invention;

Figure 2 is a side elevation of the bathing implement shown in Figure 1; and

35 Figure 3 is a vertical sectional view taken on line 3—3 of Figure 1.

Referring now to the drawing in which similar reference characters denote corresponding parts in all of the figures, 2 indicates a substantially boat-like shaped frame, preferably made of wood.

40 Frame 2 includes curved side boards 3, united at their front ends by means of a wedge-shaped filler 4 and connected at their rear ends in spaced relationship by means of a cross board 5. Top plates 6 and 7 mounted on side boards 3 partly

45 close the front and rear ends of said frame. The front top plate 6 arranged at the front end of frame 2 extends slightly beyond the rounded edge 8 of frame 2 and forms a perforated ear portion 9 for connection of a rope to said frame if so desired, and the rear top plate 7, curved at its front edge 11, extends with its rear edge 11' substantially beyond said cross board 5. A seat 12, arranged in the central area of frame 2 spaces side boards 3 with respect to each other and thus assures a sturdy compact frame structure. Seat 12 embodies the wooden side brackets 14 inclined 50 with respect to the axis of frame 2 which brackets

at their inclined bottom edges 15 are interconnected with each other by means of bars 16 and thus form an inclined seating surface 17, and which also are interconnected at their inclined sides 18 by means of bars 19 to form an inclined back support 20. The bottom edges 15 of brackets 14 extend substantially beyond the lower edge 3' of side boards 3 so that the seating surface 17 is located substantially below the lower edge of said boards to insure a low center of gravity, when the 10 implement is floating with a person resting on seat 12.

An air inflated rubber tube 21, preferably an ordinary tire tube, is tightly drawn around the frame 2 and follows the outline of said frame, 15 thus forming a pointed boat-like structure adapted to cut the water when propelled and permit readily and easily steering while floating. Rubber tube 21 is held against disconnection from frame 2 by perforated ear 20 portion 9, by rear top plate 7 and by the valve member 22 of said tube which extends through a perforation 23 in said board into the interior of frame 2. This arrangement protects valve member 22 against accidental actuation and prohibits 25 injury to persons mounting the bathing implement. A plurality of belts 24 interlock side boards 3 and tube 21 and a belt 25 may be utilized to secure a person to seat 12, if so desired.

In connecting tube 21 to frame 2 such tube is 30 preferably slightly inflated, then pulled over said frame, thereafter fastened by belts 24 and finally more tightly inflated, so that the tube is rigidly secured and held in place.

From the above description it will be clear that 35 the device of the character described, embodies features of advantage all as set forth, and that such device is susceptible of modification in minor particulars without departing from the spirit and scope of the appended claim.

40 What I claim is:

A buoyant boat-like bathing implement, comprising an elongated rigid frame including spaced side-boards joined at their front ends at an acute angle and a vertical cross wall connecting the 45 rear spaced ends of said side boards, an air inflated rubber tube stretched under tension around the said frame for snugly engaging the outside faces of said side boards and cross wall and forming an acute angular bent in said tube 50 opposite the joined front ends of said side boards, said air inflated tube including a valve member having its body laterally extended through an opening in said vertical cross wall into the interior of said frame for interlocking engagement of 55 said frame and tube.

EMMA C. HEGEWALDT.
